UNITED STATES PATENT OFFICE.

FRANK A. SCHUSTER, OF PITTSBURG, PENNSYLVANIA.

GATE-OPENER.

No. 922,963.

Specification of Letters Patent.

Patented May 25, 1909.

Application filed December 4, 1908. Serial No. 465,909.

To all whom it may concern:

Be it known that I, FRANK A. SCHUSTER, a resident of Pittsburgh, South Side, in the county of Allegheny and State of Pennsylvania, have invented a new and useful Improvement in Gate-Openers; and I do hereby declare the following to be a full, clear, and exact description thereof.

My invention relates to devices for opening and closing swinging gates, and has special reference to such devices operated by the vehicle in passing over the same.

The object of my invention is to provide a cheap, simple and efficient apparatus for opening and closing swinging gates through the wheels of a vehicle engaging with such devices in such a manner that the gates will be insured of opening and closing when desired in driving in either direction, as well as providing such an apparatus which will not be liable to get out of order, and can be operated by hand if desired.

My invention consists, generally stated, in the novel arrangement, construction and combination of parts, as hereinafter more specifically set forth and particularly pointed out in the claims.

To enable others skilled in the art to which my invention appertains to construct and use my improved apparatus for opening and closing swinging gates, I will describe the same more fully, referring to the accompanying drawing, in which—

Figure 1 is a top plan view of a pair of swinging gates showing my invention applied thereto. Fig. 1^a is a like view of one side of the apparatus showing the same in another position and with one of the gates opened. Fig. 2 is a view showing an elevation of the apparatus on the inner side of the gates and a central section through one of the operating devices on the outer side of the same. Fig. 3 is an enlarged side view of one of the gates. Fig. 4 is an enlarged detail view of one of the operating devices. Fig. 5 is an enlarged top view of one of the gates.

Like symbols of reference herein indicate like parts in each of the figures of the drawing.

As illustrated in the drawings, 1 represents a pair of swinging gates in a drive-way A, which are vertically hung on the inner sides of the same from the side posts 2 by the hinges 3 connected to said gates and fitting loosely around the vertical bars 4 supported on said posts, and each of said bars has a

spiral spring 5 around the same and connected thereto at one of its ends, while the other ends of said springs are adapted to bear against said posts.

60

Connected to the lower end of each of the bars 4 is an arm 6 which extends under said gates from their inner sides a to the outer sides b of the drive-way A and said gates, and a rope or chain 7 is connected at one end to

65

each of said arms and passes around a pulley 8 in a bearing 9 on the inner side of the drive-way A and on each side of the same. A rope or chain 7' is connected at one end to the rope

70

or chain 7 and passes around a pulley 8' in said bearing, and the rope or chain 7 passes from its pulley 8 into a pipe 10 extending under the gates 1 from the one side of said bearing to the outer side of said gates and secured in bearings 11 on each side of the drive-

75

way A, while the other rope or chain 7' passes from its pulley 8' into a like pipe 10 extending from the other side of the said bearing on the inner side of said gates and secured in like

80

bearings 11 on each side of said drive-way. The ropes or chains 7 and 7' are each connected at their other ends to one end of a spiral spring 12' in each of the pipes 10, and the opposite end of said spring is connected to one end of a rod 12 which passes through

85

the outer ends of said pipes and is connected at its other end to one end of a lever 13 of the operating devices 14. These operating devices 14 are four in number, two being located on each side of the gates 1 and each of such

90

set of two being located on each side of the drive-way A.

The levers 13 of the operating devices 14 are each adapted to fit loosely at their ends around a pin 14' rigidly mounted in a bearing 95 block 15 in said devices and passing through a boss 16 above said ends and through a gear segment 17 at the upper end of said boss. An operating bar 18 extends through and is journaled in each of the blocks 15 and in the bearing 19 at the inner ends of the same, and such ends are provided with a crank portion 20 within the same. A gear segment 21 is loosely mounted on each of the bars 18 for engagement with the gear segment 17 on the levers

100

13 and the hub 22 on the segment 21 is provided with a raised portion or lug 23 to engage with the crank 20 on said bars in operating said segments 17 and 21. The outer ends of the bars 18 are loosely connected to

105

one end of the rods 24 which are mounted in bearings 25 and are provided with a crank

110

arm 26 at their inner ends connected to said bars and engaging with a pin 18' thereon. An arm 24' is formed on the outer ends of the rods 24 and a rod 27 is adapted to be connected to said arms on the inner side of the gates 1 and the inner ends of the two spring latches 28 and one end of the levers 33 on the outer side of the said gates. These latches 28 are each located on the inner side of the 10 drive-way A and on each side of the same and are pivotally mounted at 29 in a bearing 30 on a post 31, while the outer ends of said latches are connected by the rods 32 with the arms 24' on the outer side of the said drive-way and with one end of the levers 33 on the 15 inner side of said drive-way. The levers 33 are pivotally mounted on a pin 34 in a bearing 35 and are provided with a stop portion 36 at the other ends of the same. A spiral 20 spring 34' is connected around the pin 34 and is secured at its ends to the bearing 35 and the portion 36 on the levers 33.

Extending out from the upper ends of the bars 4 is an arm 37 which is connected to the 25 handle end 38' of a bell crank lever 38 pivoted on the gates 1 through a jointed rod 39, and a vertical rod 40 connects the other end 38'' of said lever with a lug 41' on a spring latch 41 secured to the under face of said gates. Each of the latches 41 on the gates 1 are adapted to engage with a central block 42 located in the drive-way A, and such block is provided with sloping or inclined sides 42' and with a slot 43 within the same for the 30 reception of said latches when the said gates are in their closed positions to lock the same. A lug 44 is formed on the gates 1 for the arms 37 to engage with in the closing of said gates.

The use and operation of my improved apparatus for opening and closing swinging gates is as follows—With the parts in position as shown in Fig. 1, and the gates 1 closed, the wheels of a vehicle to operate said gates will strike the crank 20 in moving toward said gates on either side of the same, and depress or rock said cranks toward said gates, as shown by the dotted lines of the inner drive-way side a Fig. 2, so that the vertical portion of said cranks will engage with the lugs 23 on the hub of the gear segments 21, to rotate said segments and in turn the segments 17 carrying the levers 13, which will move said levers in a direction away from said gates. These levers 13 in their 55 rearward movements will operate through the rods 12, springs 12' and chains 7 to rotate the spring hinge bars 4 upon the gates 1 through the arms 6 on said bars, and as the bars 4 are thus rotated the gate latches 41 are first operated by being released through the lugs 44 at the tops of said bars drawing upon the jointed rods 39, which in turn operate the bell cranks 38 to lift the said latches from their seats 43 in the blocks 42 and 60 through the connecting rods 40 to open the

gates 1. While the latches 41 are thus being released in the manner just described, the springs 12' connecting the chains 7 with the rods 12 to levers 13 are being extended, so that as soon as said latches are released the 70 gates 1 are operated quickly by such spring action, and the opening of said gates is completed by the further movement of said levers until said gates reach the open position shown in Fig. 1^a, while at such time the 75 said gates are held open by the spring latches 28. When the levers 13 reach their most rearward position they engage with the spring actuated stop levers 33 and passing same they are held in their rearward positions by the stop portions 36 on said levers 33. After the gates 1 are thus opened they are held on the inner side a of the drive-way A and at the sides of the same by means of the latches 28 engaging with the sides of the 80 same until the vehicle in passing through the gates and upon the wheels of the vehicle coming in contact with the crank arms 20 on the outer side b of the said drive-way they will depress said arms in a direction away 85 from the gates 1. In this movement of the cranks 20 the gearing 17 and 21 on the outer side b of the drive-way A will not be operated by reason of said cranks moving away from the lugs 23 on gear segments 21, but operated only to rock the shafts 18 of said cranks and rods 24 through the pins 18' on said shafts engaging with the arms 26 on said rods, which rocking movement operates 90 through the rods 32 to operate the latches 28 and release the gates 1 which are held closed by the springs 5 on the bars 4 through the arms 37 contacting with the lugs 44 on said gates. The rods 32 being continued past the 95 latches 28 and attached to the ends of stop levers 33 will act to release the arms 13 from the levers 33 simultaneously with the releasing of the gates 1 and thus allow all the previously operated parts to assume their normal 100 positions. As the gates 1 close the latches 28 and attached to the ends of stop levers 33 will act to release the arms 13 from the levers 33 simultaneously with the releasing of the gates 1 and thus allow all the previously operated parts to assume their normal 105 positions. As the gates 1 close the latches 28 and attached to the ends of stop levers 33 will act to release the arms 13 from the levers 33 simultaneously with the releasing of the gates 1 and thus allow all the previously operated parts to assume their normal 110 positions. As the gates 1 close the latches 28 and attached to the ends of stop levers 33 will act to release the arms 13 from the levers 33 simultaneously with the releasing of the gates 1 and thus allow all the previously operated parts to assume their normal 115 positions. As the gates 1 close the latches 28 and attached to the ends of stop levers 33 will act to release the arms 13 from the levers 33 simultaneously with the releasing of the gates 1 and thus allow all the previously operated parts to assume their normal 120 positions. As the gates 1 close the latches 28 and attached to the ends of stop levers 33 will act to release the arms 13 from the levers 33 simultaneously with the releasing of the gates 1 and thus allow all the previously operated parts to assume their normal 125 positions. As the gates 1 close the latches 28 and attached to the ends of stop levers 33 will act to release the arms 13 from the levers 33 simultaneously with the releasing of the gates 1 and thus allow all the previously operated parts to assume their normal 130 positions.

It will thus be seen that my improved devices for operating swinging gates will enable them to be handled automatically by the 125 wheels of the vehicle passing over the drive-way and from either side of said drive-way, as well as such devices will enable the gates to be operated by hand, and all the parts being exposed and above the ground will per-

mit their being kept in operative form and easily repaired.

The parts are strong and durable, are easily assembled and are not liable to be affected by the weather or elements, either in their operation or wear.

The devices can be applied to a single gate, and various other modifications and changes in the design, construction and operation of the various parts of my improved devices for operating swinging gates may be resorted to, without departing from the spirit of the invention or sacrificing any of its advantages.

What I claim as my invention, and desire to secure by Letters Patent, is—

1. The combination with a swinging gate, of a latch carried by said gate, cranks adapted to be engaged by the wheels of a vehicle passing over the same, gearing mechanisms connected to said cranks, and a connection between said mechanisms and latch comprising two rods and an interposed spring for latching and unlatching said gate.

2. The combination with a swinging gate, of a latch carried by said gate, cranks adapted to be engaged by the wheels of a vehicle passing over the same, gearing mechanisms connected to said cranks, and rods having springs interposed therein, said rods passing over pulleys and connected to said mechanisms and to said latch for latching and unlatching said gate.

3. The combination with a swinging gate, of a latch carried by said gate, cranks connected to said latch and adapted to be engaged by the wheels of a vehicle passing over the same, and means for holding said cranks down until the gate is opened.

4. The combination with a swinging gate, of a latch carried by said gate, cranks connected to said latch and adapted to be engaged by the wheels of a vehicle passing over the same, and levers for holding said cranks down until the gate is opened.

5. The combination with a swinging gate, of a latch carried by said gate, cranks connected to said latch and adapted to be engaged by the wheels of a vehicle passing over the same, and spring operated levers for holding said cranks down until the gate is opened.

6. The combination with a swinging gate, of a latch for holding said gate in its open position, cranks connected to said gate and adapted to be engaged by the wheels of a vehicle passing over the same to open and close said gate, means for holding said cranks down until the gate is opened, and means connected to said cranks and said means for releasing said gate.

7. The combination with a swinging gate, of a latch for holding said gate in its open position, cranks connected to said gate and adapted to be engaged by the wheels of a vehicle passing over the same to open and close said gate, means for holding said cranks down until the gate is opened, and rods connected to said cranks and said means for releasing said gate.

In testimony whereof, I, the said FRANK A. SCHUSTER, have hereunto set my hand.

FRANK A. SCHUSTER.
